UNITED STATES PATENT OFFICE.

CHARLES R. DENNISON, OF YOUNGSTOWN, OHIO.

AMALGAMATOR.

1,111,251.

Specification of Letters Patent. Patented Sept. 22, 1914.

Application filed June 4, 1913. Serial No. 771,736.

To all whom it may concern:

Be it known that I, CHARLES R. DENNISON, a citizen of the United States, residing at Youngstown, in the county of Mahoning 5 and State of Ohio, have invented certain new and useful Improvements in Amalgamators, of which the following is a specification.

This invention relates to improvements in amalgamators and its principal object resides in the provision of a machine of simple construction which while having a large amalgamating surface, requires in its operation but a small quantity of mercury for 10 the amalgamation of all the values contained in the pulp under treatment.

A further object of my invention resides in the provision of a retort in which the mercury contained in the amalgam discharged from the machine, is vaporized and from which it is returned to the amalgamating element of the apparatus, and still other objects of my invention reside in constructing the machine so as to render the amalgamating element thereof readily removable 20 and accessible, and in providing a suction means which draws the pulp along the amalgamating surfaces and conveys the tailings to a point of discharge and which 25 thereby renders the process substantially continuous.

I attain the above stated objects by the mechanism illustrated in the accompanying drawings in the various views of which like 30 parts are similarly designated, and in which,

Figure 1 represents a vertical, longitudinal section through the apparatus, partially in elevation, Fig. 2, a transverse section taken along the line 2—2, Fig. 1, Fig. 3, 40 a transverse section along the line 3—3, Fig. 1, Fig. 4, a longitudinal section along the line 4—4, Fig. 2, drawn to an enlarged scale, and Fig. 5, a section along the line 5—5, Fig. 2.

Referring to the drawings by numerical reference characters, 2 designates a preferably rectangular tank which in its bottom portion supports a cylindrical conduit 4. The conduit has at one of its ends a concentric opening of smaller diameter which connects with a feed chamber 5 formed in the tank by means of a transverse partition 6 and it connects at its opposite end with an upright discharge flue 7 through which 50 the tailings are removed from the machine.

A spiral screw 8 at the end of a vertical

shaft 9 is rotatably disposed at the lower end of the flue to create by its rotary motion, a suction which will cause the tailings discharged from the cylinder to be drawn 60 upwardly into the flue to an overflow point which is designated by the numeral 10 in Fig. 1. The lower portion of the flue has interiorly, an inwardly projecting spiral rib 12 which serves to counteract the whirling 65 motion imparted to the upwardly drawn material by the action of the screw, and which thus accelerates the flow of the material to the point of discharge.

The cylindrical conduit 4 is divided into 70 two sections the lower one 3 of which is fixed in the tank, while the upper one 13 is loosely supported upon the edges of the lower section and held against lateral displacement by means of flanges 14 which connect the stationary part with the longitudinal walls of the tank.

The removable section of the cylinder carries at its ends by means of radial spokes 15, two bearings 16 for the support of a shaft 80 17, and the two sections of the tank are reinforced by means of T-shaped hoops 18 which are likewise divided into two parts.

The shaft 17 connects at a point inside the feed chamber by means of a clutch 19, 85 with a driving shaft 20 which projects through a bearing 21 applied in an opening in the adjacent end wall of the tank, and which in the operation of the machine is connected with a motor or other conveniently located motive agent. The shaft whose longitudinal axis is coincident with that of the cylinder 4, carries a double helical screw-blade 22 which is composed of wire screen and which is firmly secured to 90 spokes 23 radiating from the shaft and, at its peripheral edges, to a surrounding cylinder 24 which is made of similar material.

The perforated cylinder and screw mounted on the shaft 17 constitute the amalgamating element of the apparatus which when the shaft is rotated, dips into a quantity of mercury contained in the bottom portion of the cylindrical conduit, as is indicated at 25 in Fig. 1 of the drawings.

The crushed ore and water which in the form of a pulp are fed into the chamber 5, are by the rotary motion of the spiral screen and the suction created by the screw 8, drawn through the conduit into the flue 7 and in their course through the conduit are continually brought in intimate contact

with the surfaces of the amalgamating element and the mercury which adheres thereto, with the result that the latter amalgamates with the metallic values contained in the pulp, while the tailings are drawn into the flue and discharged over the over-flow 10 into a suitable receptacle or conveyer. The amalgam which falls to the bottom of the conduit is discharged therefrom through a number of outlet pipes 26 which by means 15 of a header 27 and a pipe 31 are connected with the retort 28 shown in Fig. 2, in which it is subjected to artificial heat for the purpose of vaporizing the mercury which subsequently is returned to the cylinder 4 through a pipe 29, which by means of a header 30 is connected with a plurality of openings in the removable section of the conduit.

While the retort employed in coöperation 20 with the amalgamating element of my invention may be of any suitable construction, I preferably use a device of the construction illustrated in the drawings in which the pipe 31 through which the amalgam is removed from the conduit 4, and the pipe 29 through which the volatilized mercury is returned to the same, are attached respectively to hollow heads 32 and 33 which are connected by means of a plurality of tubes 34.

The structure composed of the heads and tubes is inclosed in a casing 35 which at its lower end communicates by means of a duct 36 with a source of heat, as for example the exhaust pipe of a steam or internal combustion engine used to operate the rotary elements of the amalgamator, and which at its upper portion has an outlet 37 for the discharge of the gases after they have communicated their heat to the contents of the structure into which the amalgam is introduced.

The mercury contained in the amalgam being volatilized by the heat of the gases flowing through the casing 35, is returned 45 to the conduit 4 of the amalgamator as hereinbefore explained, and the gold or other metal which was united with the mercury, falls into the lower head 32 from which it may be removed through a valve controlled 50 outlet pipe 38.

When it is desired to examine or inspect the amalgamating element of the apparatus the same may readily be removed by disconnecting the upper header 30 from the pipe 55 which connects it with the retort and lifting the upper section of the cylindrical conduit together with the shaft 17 after the latter has been disconnected from the driving shaft by separating the members of the clutch.

By bending either the revolving cylinder 24 or the lower half of the conduit 4, the distance between the two is enlarged at the bottom portion of the latter as is indicated 60 at 39 in Fig. 2, for the purpose of providing

a clear space in which the amalgam may collect it before it is discharged through the outlets 26.

Having thus described my invention what I claim and desire to secure by Letters-Pat- 70 ent is:

1. An amalgamator comprising a mercury container, a rotary amalgamating element disposed to move through mercury in said container and composed of a shaft, a cylinder concentric therewith and a helical blade the edges of which engage the surface of said shaft and the inner surface of said cylinder whereby to divide the space between the two into a continuous spiral passage, 80 the said cylinder and the said blade being composed of foraminous material, means for feeding ore into an end of said cylinder, and means for the removal of tailings discharged through its opposite end. 85

2. An amalgamator comprising a mercury container, a rotary amalgamating element disposed to move through mercury in said container and comprising a continuous spiral conduit of foraminous material, 90 means for feeding ore into one end of said conduit, and means for the removal of tailings discharged through the opposite end of the same.

3. An amalgamator comprising a cylindrical casing, a rotary amalgamating element disposed to move through mercury contained in the bottom portion thereof and composed of a continuous spiral conduit of foraminous material, means for feeding ore 100 into an end of said conduit and means for the removal of tailings discharged through the opposite end of the same. 95

4. An amalgamator comprising a cylindrical casing, a rotary amalgamating element disposed to move through mercury contained in the bottom portion thereof and composed of a continuous spiral conduit of foraminous material, means for feeding ore into an end of said conduit and means for 110 the removal of tailings discharged through the opposite end of the same, the said bottom portion of the casing being spaced from the exterior surface of the said amalgamating element to provide a settling space for 115 the mercury.

5. An amalgamator comprising a container the bottom portion of which constitutes a settling space for mercury, and an amalgamating element of foraminous material rotatably mounted in said container and provided with means for conveying material from one of its ends to the other, the said container having outlets for the discharge of amalgam from the said space, and in its 120 upper portion, inlets for the distribution of mercury over the said rotary element. 125

6. An amalgamator comprising a container, and an amalgamating element rotatably mounted therein and composed of a 130

shaft, a cylinder concentric therewith, and a helical blade the edges of which engage the surface of said shaft and the inner surface of said cylinder whereby to divide the space 5 between the two into a continuous spiral passage, the said cylinder and the said blade being composed of foraminous material.

7. An amalgamator comprising a cylindrical container, and a cylindrical amalgamating element rotatably mounted therein 10 and comprising a continuous spiral conduit of foraminous material, the outer surface of said element moving in close proximity to the wall of said container.

15 8. An amalgamator comprising a cylindrical container the bottom portion of which constitutes a settling space for mercury, and

a cylindrical amalgamating element of foraminous material mounted in said container to move in close proximity to its peripheral wall and provided with means for conveying material from one of its ends to the other, the said container having outlets for the discharge of amalgam from the said space, and in its upper portion, inlets for 20 25 the distribution of mercury over the said rotary element.

In testimony whereof I have affixed my signature in presence of two witnesses.

CHARLES R. DENNISON.
